MANUFACTURE OF ALKYL ARYL SULFONATES

James W. Putt, Los Angeles, Calif.

Application April 24, 1952, Serial No. 284,041

21 Claims. (Cl. 260—505)

This disclosure is concerned with a very economical method for the manufacture of surface active agents and synthetic detergents, particularly with the active ingredient of such synthetic detergents.

Generally speaking, there are three classes of surface-active agents: anionic, cationic and nonionic. Furthermore, there are various types of organic chemical compounds included in each class. For instance, the anionics may include salts of (1) alkyl sulfates, (2) long chain fatty acids and (3) sulfonic acids of mononuclear and polynuclear aromatic hydrocarbons, their alkylated derivatives and other derivatives of such hydrocarbons. The present invention is especially concerned with the sulfonic acid of alkylated aromatic hydrocarbons, and salts of such acid. A salient object of this invention is to devise a process whereby such salts can be prepared in a high degree of purity in a very economical manner.

The greatest proportion of the alkyl aryl sulfonate type of surface active agent sold at present consists of the sulfonate of dodecyl benzene. Its manufacture involves the following general steps:

1. Preparation of dodecene.
2. Alkylation of benzene by reaction with at least an equivalent quantity of dodecene to form dodecylbenzene followed by its separation and purification.
3. Sulfonation of the dodecylbenzene with a large excess of fuming sulfuric acid.
4. Neutralization of the sulfonation mixture to yield the active, sodium dodecyl benzene sulfonate, admixed with a large proportion of sodium sulfate.
5. Extraction of the sulfate-sulfonate mixture with ethyl alcohol to separate the sulfonate and separation of the alcohol therefrom.

6. Drying.
Builders such as polyphosphate, borax, carbonate may be added before or subsequent to step 6. To a large extent step 5 is a present omitted because it is very expensive, and because the product otherwise would be hygroscopic. The omission, of course, leaves a product with a very large proportion of sodium sulfate, an undesirable feature because it limits the concentration of surface active agent in the finished detergent and causes a disagreeable reaction of the detergent on the hands of the user.

It should be pointed out, furthermore, that benzene is now in short supply and therefore is commensurately expensive. While the supply may be improved in the future as a result of its manufacture from petroleum naphtha, substantial reduction in price is not foreseen because of the production in massive amounts of a large number of substances requiring benzene and also because of the substantial cost of producing benzene from the particular narrow boiling fraction of the particular type of petroleum naphtha required.

In the new method of the invention for the production of alkyl aryl sulfonates, both the starting substance and the steps of the process are modified in a novel manner so that the product is obtained at a vastly reduced cost.

2

In the new method the olefin employed may be the same as the dodecene used in most of the alkyl aryl types of active sold heretofore. However, the process is not limited to dodecene. For instance, tripolyethylene (nonylene) diisobutylene and triisobutylene have been employed to yield a very successful product.

While benzene may be used as the aromatic hydrocarbon, it is by no means essential. In the new method it is displaced by a mixture of aromatic hydrocarbons particularly those boiling between 390° F. and 600° F. or preferably between 400° F. and 550° F. Essentially this mixture consists of alkyl naphthalenes with or without naphthalene itself. While it is preferable that this mixture be substantially free from non-aromatic hydrocarbons, it is not essential because they are subsequently eliminated in the process. The required hydrocarbons, constituting the starting material, may be obtained from coal tar or the like. In sharp contrast with benzene, the chemical demand for the 390° F.—600° F. is not great. It is easily procurable at a steady price. Furthermore, especially of great importance this fraction forms a large proportion of the product from the subjection of certain petroleum fractions of wide boiling range in accordance with my Patent No. 2,207,552, and may be derived from such product by simple fractionation.

As hereinabove stated, the prevalent method used for the production of alkyl aryl sulfonates involves the interaction of benzene and at least an equimolecular quantity of olefin, followed by the isolation and purification of alkylated benzene and the sulfonation of this product with fuming sulfuric acid in a distinctly separate step. In striking contrast, in the new method, sulfonation takes place in the same kettle in which the alkylation step is carried out without any prior separation whatsoever. Aromatic hydrocarbon, olefin and sulfuric acid are all mixed in a kettle to yield the desired sulfonic acid of the alkylated aromatic hydrocarbon in one simple process step. While due to the possibility that alkylation proceeds at a faster rate than does sulfonation, alkylation may actually take place first, followed by sulfonation, to all intents and purposes from a practical standpoint, alkylation and sulfonation are carried out in one step with a great saving in plant installation cost and operating cost.

The new method has a further important economic advantage in that it has been found that because of peculiar properties of the mixture of aromatic hydrocarbons, an equimolecular quantity of olefin is not required. In fact, as little as 30% of an equimolecular quantity of olefin gave a good product. This is quite an economic advantage in view of the fact that the olefin is more costly than the aromatic hydrocarbon mixture especially when the latter is prepared in accordance with Patent No. 2,207,552. Furthermore, in the presence of so low a relative quantity of olefin there is very little or no likelihood for polyalkylation and esterification of the sulfonic acid to take place.

The aromatic mixture used in the process is much more easily sulfonated than is benzene. As a result the sulfonation can be carried out with 98% sulfuric acid although fuming acid can be used. With benzene 98% acid would not be suitable. However, it has been found that the required reaction can be carried out with greater facility by using stronger acid than 98%, preferably by starting out with 98% sulfuric acid to the extent of about 30%—60% of the total acid required and then completing the reaction with stronger acid such as 5% to 20% fuming sulfuric acid.

It has been stated above that the sulfonation of dodecyl benzene requires a large excess of sulfuric acid. This is also true in the case of the mixture of aromatic hydrocarbons used in the present process. However, in the

case of dodecyl benzene, the dried sodium salt of the sulfonic acid is quite hygroscopic and is therefore sold in admixture with a high concentration of sodium sulfate in order to overcome this difficulty. To provide this sodium sulfate, the excess sulfuric acid is neutralized together with the sulfonic acid. A product containing sodium sulfonate admixed with a large proportion of sodium sulfate results. This operation necessarily requires a large expenditure of sodium hydroxide. This is disadvantageous because it depreciates a large quantity of sulfuric acid, a fact of quite some concern in these days of short supply of sulfur. It consumes large quantities of sodium hydroxide and results in a product with a low concentration of active. Furthermore, when even despite the hygroscopicity, a product with a high concentration of surface active agent is desired, the expensive step of alcohol extraction has to be resorted to because of the large quantity of sulfuric acid that remains dissolved in the sulfonic acid.

With the aromatic mixture used in this process, however, the resulting sodium sulfonate is non-hygroscopic and can thus be maintained exposed to ordinary atmosphere without danger of caking or of any other defect. Because of the high concentration in which the surface active agent can be prepared, the range of finished detergents has been enhanced tremendously. Furthermore, this high concentration of surface active agent can be procured quite simply because the greater part of the excess sulfuric acid separates by gravity from the sulfonic acid and is therefore easily recovered therefrom. A further quantity of sulfuric acid is obtained upon centrifuging the sulfonic acid layer. As will be appreciated, the ability to recover this excess acid results in three very important economic advantages: The recovered sulfuric acid is made available for further use, a factor of extreme importance because of the very short supply of this commodity. Secondly, a great saving in the cost of alkali is achieved because alkali does not have to be used to neutralize this excess acid. Finally, the surface active agent is recovered in very high concentrations because it is not accompanied by very large quantities of sodium sulfate as in the prior processes.

Any residual sulfuric acid remaining admixed with the sulfonic acid is removed by conversion by addition of lime to calcium sulfate and separated by filtration. Thus the process is capable of producing surface active agent accompanied by little or no sodium sulfate although a small proportion is allowed to remain because it acts as a builder.

In order to insure a clear understanding of the new process and an evaluation of its merits, reference is made to the accompanying drawing which illustrates but one embodiment of the process.

As shown in the drawing, a petroleum oil, preferably one the major portion of which boils between 400 and 600° F. is taken from storage 1 and is continuously passed to an extraction unit 2. Any solvent such as sulfur dioxide, furfural or the like which will efficiently separate the paraffins from the other hydrocarbons, particularly the aromatics and olefins, may be employed. Treatment in the extraction unit leads to the formation of a raffinate which is withdrawn through line 3 and an extract withdrawn through line 4. The solvent is removed from both the raffinate and extract by suitable means not shown. The raffinate is removed from the system as one of the end products of the process.

The extract is then subjected to cracking at elevated temperatures particularly in the presence of an extraneous gas. In the particular embodiment chosen, air is used as the extraneous gas which serves to provide autogenous heat. The extract is pumped to a heater 5 where it is heated to about 700° F. and thence conducted to line 6 where it meets and is mixed with a stream of heated air. This air had previously been passed at a predetermined

rate through compressor 7 and heater 8 before it comes in contact with the heated stream of extract in line 6.

The air reacts with some of the heated oil resulting in an increase in temperature to the desired level of about 1050° F. to 1200° F., preferably between 1125° F. and 1175° F. As is well understood, the quantity of air in relation to the amount of extract undergoing cracking, and the temperature of both the oil and air are chosen to provide the desired reaction temperature. Air heater 8

10 may be dispensed with or operatively removed from the system is necessary by providing relatively more air. The intermingled stream of heated oil and air or the products derived from such intermingling are passed through reaction vessel 9 where a complex series of reactions including dehydrogenation, cyclization, side chain removal, 15 cracking and polymerization takes place. As a result of this complex reaction, complete or substantially complete aromatization occurs, depending upon the gravity and boiling range of the raw charge and reaction temperature.

20 The product from reactor 9 is conducted through a series of separators 10, 11 and 12. From separator 10 a heavy residual oil is removed through line 13. This residual oil is further processed to yield pitch with a desired melt point. The vapors from separator 10 are fractionated

25 in vessel 11 from which is discharged an overhead containing light products and water formed from the action of the air and extract. The light products contain combustion products, hydrogen, methane, other paraffins and olefins with 2 to 5 carbon atoms and aromatics with

30 6 to 9 carbon atoms. This overhead is passed through condenser 14 and accumulator 15 wherein water is allowed to separate and is discharged therefrom through line 16. Some light oil is returned by means of pump

35 17 as reflux to fractionator 11. The remainder is discharged through line 18 to storage. This oil may be refined by treatment with sulfuric acid as is well understood and a pre-benzene cut removed by fractionation. The remainder containing toluene, xylenes, a mixture of

40 C₈ aromatic hydrocarbons together with a small quantity of benzene may well be employed as aviation rich mixture or separated into individual components. Alternatively the light oil may first be fractionated, particularly to separate alpha methyl styrene, before being subjected to chemical treatment.

45 The uncondensed portion of the products may be separated in accumulator 15, discharged through line 19 and conducted to an absorption system to recover condensable products therefrom and may then be employed as fuel or flared.

50 The portion of the product in tower 11, boiling generally above 390° F., leaves the tower at the bottom and is passed to fractionator 12. Herein detergent stock boiling between 390° F. and 550° F. is separated as an overhead from a heavier and higher boiling oil which has the characteristics of anthracene oil. The anthracene oil is discharged from tower 12 through line 20 to storage. This oil may be later treated to separate carbazole-free anthracene suitable for oxidation to anthraquinone.

The detergent stock leaves as vapor from the upper 55 portion of tower 12, is passed through cooler 21, thence to accumulator 22. A portion is returned as reflux by means of pump 23 to tower 12 and the remainder converted to detergent. Dependent upon factors extraneous to the matter of detergents, it may be desirable to separate

60 a part or all of the naphthalene from the detergent stock. This can be done in any known manner, such as by close fractionation. The naphthalene can then be marketed as such or converted to derivatives such as phthalic anhydride, beta-naphthol, naphthyl amine or to a detergent of the type herein described.

65 Before the detergent stock is converted, however, it has to be chemically treated. The art of treating detergent stock is the same as that practiced in the preparation of pure aromatic hydrocarbons such as benzene and toluene, destined for the manufacture of dyes and medi-

cinals. Therefore, the treating process will not be described in detail. However, it should be noted that the detergent stock should first be treated with alkali to remove phenolic compounds, then with acid recovered in a later step, to extract nitrogen bases. The phenolic compounds and nitrogen bases can be recovered by neutralizing their respective solutions. It is economically advantageous to do this.

After the oil has been freed from acidic and basic constituents, it is treated one or more times with a relatively small amount of sulfuric acid. Spent acid obtained in a later step can advantageously be employed for at least a part of the refining treatment followed by commercial 66° Bé. sulfuric acid in an amount equal to a total of from 10 to 20 lbs. per barrel, in two steps. With proper care known in the treating of aromatic hydrocarbons and lubricating oil, the acid-treated oil is washed and then redistilled. It is then ready for conversion to active or detergent.

The description of the new process followed to convert the detergent stock into surface active agent and detergent may be more easily understood by study of the following equations which reflect the series of reactions taking place. It is to be noted first that the detergent stock is a mixture of aromatic hydrocarbons composed substantially of naphthalene and its various alkylated derivatives. To facilitate the exposition, the conversion of 1,2 dimethyl naphthalene to the corresponding nonyl naphthalene sodium sulfonate will be used merely as an illustrative example. All the other aromatic hydrocarbons forming the detergent stock will undergo the same general type of reactions. It is to be further noted that less than one mol equivalent of nonylene is employed. Thus both naphthalene and nonyl naphthalene derivatives are present in the final product. The reactions may be represented as follows:

(1)

where R is the radical remaining upon removal of H from

The compound designated by RSO₃Na is, of course, the desired surface active agent.

In carrying out the process, the treated detergent stock is transferred to a jacketed kettle 24 equipped with agitator; the valves 26 and 27 remain closed during the whole sulfonation reaction. An olefin such as tripropylene, tetrapropylene or other olefin or mixture of olefins containing 8 to 18 carbon atoms is also charged to the kettle 24. The quantity of olefin may vary between 10 and 100 mol percent depending upon the boiling range of the aromatic hydrocarbon mixture, the olefin employed and the quality of the surface active agent desired. A surface active agent of high quality has been obtained from the use of 30 mol percent of tripropylene. The olefin and aromatic hydrocarbon are thoroughly mixed by means of the stirrer. The mixture is then subjected to an alkylation and sulfonation reaction in one step. Sulfuric acid is used in both reactions. While the stirrer is maintained in operation, sulfuric acid of 98% concentration

or stronger is at first added slowly at such rate that the temperature does not rise above about 105° F. to 110° F. A stream of cold water is passed through the jacket 25 of the kettle to control this temperature. Usually it takes 20 to 30 minutes to add the acid in a volume equal to about 1/2 of the total volume of detergent stock and olefin. When such a volume of acid has been added, another like volume of acid is added to the reaction mixture. This can be done more quickly and without the aid of the cold stream of water. A period of about 10 minutes can be taken for such addition. Thus the total volume of acid employed is equal to the total volume of hydrocarbon undergoing reaction. Stirring is preferably continued but the reaction is aided by allowing a stream of hot water to pass through the jacket to raise the temperature of the reaction mass to about 145° F. and to maintain it at this point until the sulfonation is complete.

As the reaction proceeds, the mass which is reddish in color, becomes more and more viscous. The end of the reaction is determined by noting the behavior of a drop of reaction mass on a glass wall. A shiny appearance with little tendency to flow evinces practical completion of the sulfonation. Confirmation is obtained by shaking a drop of the reaction product with a dilute solution of alkali or sodium carbonate. At the point of practical completion a large volume of dense stable suds is obtained. The entire reaction, including the time necessary for the first addition of the sulfuric acid, generally takes about 60 to 75 minutes.

Upon completion of the sulfonation reaction as shown by the above described tests, stirring is still continued but the hot water in the jacket is removed or even displaced by a stream of cold water. Water is then slowly added to the sulfonated mass until the volume of added water has reached about 15% of the total original hydrocarbon volume. The viscosity of the mass then noticeably decreases. The volume of added water is not critical. More than the noted volume may be employed without harm to the reaction. However, such increased volume increases the cost of drying the finished product. A period of about 10 minutes is generally required for the addition of the water. Stirring is then stopped and the mass allowed to remain in a quiescent state. This permits excess sulfuric acid or a part thereof, to separate as a lower layer from the sulfonic acid. Water, equal in volume to about 5% of the original total volume of hydrocarbons, is then very slowly and carefully poured down one side of kettle 24. Upon intermingling with the acid mass, the water causes the separation of a layer of oil that had not been sulfonated, either due to actual incompleteness of the reaction or because some unsulfonatable oil was originally present, or both.

With this procedure a three-layer system is obtained, the sulfonic acid being established between an upper layer of oil, generally about 10% of the volume of the original detergent stock, and a lower layer of sulfuric acid. About 20 minutes is allowed for separation to take place. The lower layer of sulfuric acid is then withdrawn through lines 33 and 28 by opening valve 27 and is passed through line 28 to storage for later concentration or conversion to useful products such as ammonium sulfate or copper sulfate. After complete removal of the sulfuric acid, valve 27 is closed and valve 26 is opened and the sulfonic acid is then separated from the unsulfonated oil and transferred to jacketed kettle 29 through lines 34 and 35 for further purification. After such separation kettle 24 is available for another sulfonation batch. If desired, the sulfonic acid may first be subjected to a centrifugal action in centrifuge 30, whereby a further amount of free sulfuric acid is separated and withdrawn through line 28. Lines 33, 34 and 35 are unusually large in diameter on account of the viscosity of the sulfonic acid which is about 5,000 cps. at 100° F.

Some free sulfuric acid amounting to about 20 to 30%

of that originally added still remains dissolved in the sulfonic acid. This is neutralized by means of lime added in kettle 29 which is equipped with stirrer. The contents of this kettle are agitated and cooled by means of a stream of cold water passing through the jacket 31. From hopper 32, lime slightly in excess of the amount equivalent to the free sulfuric acid in the sulfonic acid mass is added and caused to react with the acid mixture. Sufficient time is allowed to insure substantially complete reaction with the sulfuric acid. At least some of the excess lime neutralizes an equivalent amount of sulfonic acid. The calcium sulfonate formed, however, remains dissolved in the sulfonic acid to by far the largest extent.

After completion of the neutralization reaction, the contents of the kettle are discharged from the bottom and are passed to the filter. The calcium sulfate formed in kettle 29, together with any lime that may have escaped reaction, is thus separated from the sulfonic acid by filtration. The filtrate is then passed to neutralization tank 38. The filter 36 may be of any known type and may, if desired, even be replaced by a centrifuge.

The desired surface-active compound is the sodium salt of the sulfonic acid. The sulfonic acid is converted to its sodium salt by neutralization with an equivalent amount of sodium hydroxide solution. The quantity of alkali is very critical because the addition of too much would leave free alkali associated with the finished detergent, an undesirable situation as is now very well known. On the other hand, the use of an insufficient amount would, of course, leave free sulfonic acid. This similarly is undesirable because it would interfere with the drying of the finished detergent, would greatly decrease its quality as a washing compound and would produce a corrosive product. However, the addition of an insufficient quantity of alkali can be corrected at a later step. A very good method to follow is to add alkali until the mass becomes neutral as indicated by a pH of 7.

The solution at this point may contain a small amount of calcium sulfonate as a result of the prior addition of more lime than was necessary to neutralize the free sulfuric acid in the sulfonic acid. This calcium sulfonate is converted to the desired corresponding sodium salt by adding thereto sodium carbonate or its aqueous solution in an amount sufficient to adjust the pH from 7 to 8. The precipitated calcium carbonate formed as a result is separated from the solution of surface active agent by means of filtration in filter 39. Even if the sodium carbonate is present in the solution of the active, it does not decrease in any way the quality of the detergent because sodium carbonate is recognized as one of the detergent builders.

The last step in the process involves the removal of the water from the solution of the surface active compound. This is accomplished by transferring the filtrate from filter 39 to drier 40 wherein the water is evaporated by means of indirect heat exchange with hot gases such as hot air or hot combustion gases. This step is well known in the art and therefore need not be described. The dried surface active agent is withdrawn at the bottom either continuously through line 41 by means of a screw or intermittently. Water vapor and other gases or vapors leave the drier at the top through line 42.

Surface-active compounds in a concentration of 90% or over are obtained in this manner. Builders such as phosphates, polyphosphates, borax, carbonates or silicates may now be mixed with the surface active agent to produce a finished detergent. Other surface active agents such as lauryl sulfate and modifiers such as carboxy methyl cellulose may also be added. However, any or all of these substances may also be added to the solution of surface active agent in tank 38, wherein they can become intimately mixed, and the solution of the detergent dried in drier 40.

At times it has been found that hydrocarbon oil may remain dissolved in the solution of surface active agent. This oil reduces the quality of the finished detergent. It can be removed by washing the solution two or more times with hexane or benzene. Any of these hydrocarbons remaining after separation of the hydrocarbon layer leaves the detergent or surface active agent during the drying operation.

Returning to the sulfonation and alkylation of the aromatic hydrocarbon mixture as described above, it appears that alkylation is virtually complete before the sulfonation reaction sets in to any degree. If this were not the case, some olefin would be in contact with sulfonic acid and sulphuric acid. Both of these acids are esterification catalysts, and therefore some esterification would be expected. If esters were formed, they would be present in the oil obtained upon the careful addition of water to the sulfonic acid. This oil was analyzed and was found to contain less than 1% of sulfonic ester. In view of the fact that the volume of the oil constituted only about 10% of the volume of original aromatic hydrocarbons, ester formation took place to the extent of less than 0.1%, a negligible quantity.

The process as described involved the subjection of the raw feed to an extraction step followed by a thermal cracking reaction, to prepare the aromatic hydrocarbon mixture for the alkylation-sulfonation step in kettle 24. These steps may be modified in several ways without in any way affecting the nature nor the novelty of the process. For instance, the raw feed may be made to undergo one of several catalytic cracking processes, such as Fluid, TCC, Houdry, followed by separation of gasoline, lighter products and fuel oil, and subjection of the cracked product boiling between gasoline and fuel oil to the cracking step in reactor 9. Furthermore, instead of interacting oil vapors with air, they may be subjected to direct heat exchange relationship with hot combustion gases or any other gas heated in sufficient quantity and to a sufficiently high degree so as to heat the oil vapors in reactor 9 to a temperature of 1050° F. to 1200° F.

The cracking step of the process as effected in reactor 9 has been described as being purely thermal. However, natural or synthetic catalysts of the types used in ordinary petroleum catalytic cracking process may be employed effectively.

Furthermore, a portion of coal tar boiling between 390° F. and 600° F. before or after removal of naphthalene may be chemically treated with alkali and sulfuric acid as described above in connection with the purification of the detergent cut from accumulator 22, and then subjected to the alkylation-sulfonation reaction, without undergoing any extraction or cracking steps whatsoever, to yield an acceptable detergent.

In an example of one embodiment of the process, extract from diesel oil boiling between 407° F. and 600° F. was charged under a pressure of 60 p. s. i. g. to heater 5 at the rate of 9.3 G. P. H., and heated to a temperature of 700° F. At junction 6 the oil vapors were brought in intimate contact with a stream of air flowing through heater 8 at the rate of 320 C. F. /hr. After mixing, the temperature rose to 1170° F. Crude aromatics were formed in a volumetric yield of 77.6% which, upon distillation, gave 38.01% detergent cut, based on charge to heater 5, 4.85% aviation rich mixture, 2.18% resin cut (350° F. to 400° F.) and 32.56% anthracene oil, pitch and distillation loss. The detergent cut was treated consecutively with 35% NaOH to remove tar acids, recovered H₂SO₄ to remove tar bases, twice with 66° Bé. H₂SO₄ in a quantity of 8.6 lbs./bbl. to improve color and then redistilled. A portion of the treated detergent cut, 230 cc., was mixed with 70 cc. of tripropylene in a flask equipped with a stirrer. To the mixture in a cool water bath was added during 20 minutes 150 cc. of 98% H₂SO₄ at such rate that the temperature did not rise above 107° F. The water bath was then removed and 150 cc. more

of 98% H₂SO₄ was added during 5 minutes. The mixture was then heated on a hot water bath whereby the temperature was allowed to rise to 145° F., while the stirring of the mixture, now quite viscous, was continued. In about 15 minutes, tests as above explained, showed that the alkylation-sulfonation reaction was practically complete. 50 cc. of water was added slowly and the mixture transferred to a separatory funnel. Sulfuric acid began to separate immediately. About 20 cc. water was allowed to run down the wall whereby unsulfonated oil began to rise from the sulfonic acid. The excess acid layer was removed followed by the sulfonic acid leaving 22 cc. unsulfonated oil. To the sulfonic acid was added 50 gms. of lime, thoroughly mixed and the CaSO₄ separated by filtration. The filtrate was neutralized by adding 30% NaOH until the pH was raised to 7. The solution was then heated and to it was added a small quantity of NaCO₃ solution until the pH of the solution was raised to 8. Calcium carbonate precipitated. This was separated by filtration. The filtrate was washed twice with benzene and then heated to drive off the water. A light colored slurry was obtained which analysis showed to contain active in a concentration well over 90% on a water-free basis and in a yield of over 80% of the theoretical, based on the detergent stock charged.

The product formed a large amount of long lasting dense suds and upon a washing test after addition of sodium tripolyphosphate and carboxy methyl cellulose, was found to have a very high degree of detergency and whiteness retention.

It is to be noted that in processes known heretofore, a surface active agent with a high degree of detergency can be obtained only by extraction of the active solution with a solvent such as alcohol. This is expensive. In the described process, a product with a higher concentration of surface active agent than any anion surface active agent generally on the market is obtained without the necessity of an alcohol extraction of the sulfonate solution.

The process has been especially described in connection with the sodium salt of the sulfonic acid. Similar sulfonate of other metals or of ammonium, alkyl ammonium, or hydroxy-ammonium compounds can be prepared in the same manner by employing the oxide or hydroxide of the desired metal or ammonium derivatives as the neutralizing agent. The sulfonates of the alkaline earth metals such as calcium deserve attention, for their preparation is quite easy since all that is needed is to add an excess of metal oxide to the mixture of sulfuric acid and sulfonic acid. The calcium sulfonate solution is easily separated by filtration from the precipitated calcium sulfate and the water evaporated by known means from the solution to obtain the dry sulfonate. This saves many steps that are necessary in the preparation of the corresponding sodium sulfonate.

The method of producing anionic detergents herein described has been directed toward the fraction essentially aromatic hydrocarbons boiling between 390° F. and 600° F. as the feed to the detergent reaction. It has been found, however, that equally effective detergents can be prepared by utilizing the lower boiling aromatic oil boiling between 180° F. and 390° F., and even the broader cut boiling between about 180° F. and 600° F. as the feed. In utilizing this fraction containing the lower boiling aromatic hydrocarbons, it was found desirable but not absolutely necessary to separate the fraction boiling between about 360° F. and 390° F. from which propylene benzene can be isolated. The use of 98% sulfuric acid followed by stronger acid, as has already been described above, is of especial benefit when detergents are made from oil containing the cut boiling between 180° F. and 390° F. to 400° F.

While preferred modifications of the invention have been described, it is to be understood that these are given didactically to illustrate the underlying principles in-

volved and not as limiting its useful scope to the particular illustrated embodiments.

I claim:

1. A process of producing anionic surface-active compounds which comprises simultaneously alkylating and sulfonating a mixture of aromatic hydrocarbons having a boiling range within the limits from substantially 390° F. to substantially 600° F., with an olefin in the presence of sulfuric acid in a single reaction zone; agitating the reaction mixture in said single reaction zone until alkylation and sulfonation are substantially completely effected, adding water to the reacted mixture in amounts and under conditions controlled to effect layer separation of free sulfuric acid, unsulfonated oil and alkyl aryl sulfonic acid, separating the layers, recovering the alkyl aryl sulfonic acid and neutralizing the sulfonic acid with basic material to form the corresponding alkyl aryl sulfonates.
2. A process in accordance with claim 1 in which the quantity of olefin employed is less than an equimolar quantity of the aromatic hydrocarbons.
3. A process in accordance with claim 1 in which the sulfuric acid employed in the reaction comprises substantially 98% sulfuric acid.
4. A process in accordance with claim 1 in which the aromatic hydrocarbon mixture has a boiling range of from substantially within 430° F.-500° F.
5. A process in accordance with claim 1 in which the aromatic hydrocarbon mixture is comprised preponderantly of alkyl naphthalenes.
6. A process in accordance with claim 1 in which the aromatic hydrocarbon mixture is comprised preponderantly of alkyl naphthalene and is substantially free from basic and acidic constituents.
7. A process in accordance with claim 1 in which the aromatic hydrocarbon mixture is derived from cracked petroleum oil.
8. A process in accordance with claim 1 in which the aromatic hydrocarbon mixture is derived from coal tar distillates.
9. A process in accordance with claim 1 in which the separated alkyl aryl sulfonic acid is treated with an alkaline earth reagent in amounts sufficient to react with and precipitate any free sulfuric acid remaining in the sulfonic acid fraction neutralizing the sulfonic acid with an alkali to a pH of 8 to form the alkyl aryl sulfonate.
10. A process in accordance with claim 9 in which the sulfuric acid-free alkyl aryl sulfonate is extracted with a selective solvent to remove any contaminated unsulfonated oil.
11. A process in accordance with claim 1 in which the olefin is chosen from the group consisting of dodecene, tripropylene, diisobutylene and triisobutylene.
12. A process in accordance with claim 1 in which the aromatic hydrocarbon mixture has a boiling range of from substantially 180° F. to 600° F.
13. A process in accordance with claim 1 in which the olefin is added to the extent of 30 to 70 mol percent in relationship to the hydrocarbon.
14. A method of producing an alkyl aryl sulfonate from petroleum oil which comprises subjecting a petroleum fraction boiling within about 250° F. and 600° F. to the solvent action of SO₂ to extract the non-paraffinic hydrocarbons, separating the solvent from such non-paraffinic hydrocarbons, subjecting such hydrocarbons to cracking conditions of temperature and pressure controlled to produce a product rich in aromatic hydrocarbons; separating and recovering from the reaction products a fraction boiling between about 390° F. and 600° F. treating the separated fraction to remove therefrom the phenolic compounds and nitrogen bases; simultaneously alkylating and sulfonating the purified separated fraction with an olefin in the presence of strong sulfuric acid in a single reaction zone while agitating the reaction mixture for a period of time sufficient to substantially complete the

alkylation and sulfonation reactions; adding water to the reaction product in an amount and under conditions controlled to effect a stratification of free sulfuric acid, unsulfonated oil and the formed alkyl-aryl sulfonic acid; separating the free sulfonic acid and neutralizing the sulfonic acid with a basic material to form an alkyl aryl sulfonate.

15. A process in accordance with claim 14 in which the recovered sulfonic acid and sulfuric acid associated therewith is contacted with an alkaline earth reagent in an amount sufficient to react with the sulfuric acid and precipitate an alkaline earth sulfate, neutralizing the thus treated sulfonic acid with a basic material, separating the liquid from the precipitate, treating the neutralized product with an alkaline carbonate to yield substantially a pH of 8, and separating the precipitate by filtration from the alkyl aryl sulfonate.

16. A process in accordance with claim 14 in which the sulfuric acid employed in the reaction comprises 98% sulfuric acid.

17. A process in accordance with claim 15 in which prior to drying the alkyl-aryl sulfonate is extracted with a selective solvent to remove any contained unsulfonated oil.

18. A process in accordance with claim 14 in which the olefin is added to the extent of 30% to 70 mol percent in relationship to the aromatic hydrocarbon.

19. A process in accordance with claim 14 in which the sulfonic acid is converted to an alkali metal salt.

20. A process in accordance with claim 14 in which the sulfonic acid is converted to an alkaline earth salt.

21. A process in accordance with claim 14 in which the quantity of olefin employed is less than an equimolar quantity of the aromatic hydrocarbon.
